No 259.

Peter J. Simmons

Design for Stoves

Patented February 5, 1850

Des. 159

Peter I. Simmons of Troy, Rensselaer County,
New York Letters Patent No 259 dated February 5th 1850.

The schedule referred to in these Letters Patent and making part of the same.

To all whom it may concern.

Be it known that I Peter I. Simmons, of Troy, in the County of Rensselaer and State of New York, have invented or produced a new design of Cook Stove pattern, and I do hereby declare that the following is a full, clear, and exact description of the same, reference being had to the annexed drawings making a part of this specification in which fig. 1. is a side elevation. fig. 2. a perspective view of the front plate with one door removed therefrom, fig. 3. a view of the front plate of the fire box, shown in place in fig. 2. within the fire chamber, the projecting part of the plate at a, is for the purpose of holding the said plate in place by means of the top plate of the stove, and fig. 4. is a half view of the bottom plate of the stove from front to back.

The distinguishing features of my design of stove, consists in the form of the cornice. A moulding of the bottom plate B. and other mouldings and ornaments as represented.

The ornament on the plate C is represented in part, the other is the same reversed and corresponding with that represented.
